Patented July 16, 1918.

Inventor
LOUIS SHEINMAN

By his Attorney Benedict & Wise

UNITED STATES PATENT OFFICE.

LOUIS SHEINMAN, OF NEW YORK, N. Y.

DISPENSING ATTACHMENT FOR ETHER-CANS.

1,272,544.

Specification of Letters Patent. Patented July 16, 1918.

Application filed August 18, 1917. Serial No. 186,998.

To all whom it may concern:

Be it known that I, LOUIS SHEINMAN, a citizen of the United States, and a resident of the city of New York, county of the Bronx, and State of New York, whose post-office address is No. 944 Aldus street, Bronx, have invented a new and useful Improvement in Dispensing Attachments for Ether-Cans, of which the following is a specification.

Heretofore ether cans have been emptied for the purpose of anesthesia through rubber or cork stoppers which are attacked and ruined by the ether so that there has been a large wastage both of stoppers and ether. Furthermore, because of this wastage this ether has not been under perfect control at all times and so the patient may have suffered. The object of my invention is to provide a dispensing attachment which will be durable, tight, efficient and always under control so that the patient never suffers from defects in the apparatus and that there is no waste in material. This and other objects are accomplished by my invention, one embodiment of which is herein, more particularly set forth.

For a more particular description of my invention, reference is to be had to the accompanying drawings forming a part hereof, in which:

Figure 1 is a side elevation of a can provided with my improvement.

Fig. 2 is a plan view of the same.

Fig. 3 is a sectional view taken on the line 3—3 of Fig. 2, looking in the direction of the arrows.

Throughout the various views of the drawings, similar reference characters designate similar parts.

The ether can 1 to which my attachment 2 is applied is of the conventional kind with its flaring mouth 3 which is used when the can is either filled or emptied.

The attachment 2 has a frustum of a cone divided into two parts, 4 and 5, which are united at one end by the hinge 6 and at the other by the screw 7 which has one end pivotally mounted on one part 4 and

the winged nut 8 on this screw 7 takes over 50 the slotted ear 9 on the other part 4 so that the screw 7 may swing clear of the ear 9 when the attachment 2 is put in position or removed.

This frustum has a flange 10 at the larger 55 end which takes over a metal disk 11 which is fixed to the part 4 and carries a disk stopper 12 lined with cork or other suitable material which fits with an ether tight joint against the mouth 3 and carries also tubes 60 13 and 14, the former extending to the bottom of the can 1 and the latter is open to the bottom of the cork disk 12. The tube 14 is open to atmospheric pressure and the tube 13 has both external and internal screw 65 threads so that it may be provided with a spraying cap, as shown at 16, or a dropping device as shown at 17 or it may be used without either for a large spray stream when such is required. In any event, the 70 outflow is controlled through the kind of nozzle used and the pressure caused by the atmosphere exerted through the opening at the end of tube 14.

In view of the foregoing, the use of my 75 improvement will be readily understood. Assuming that the can 1 is received in the conventional way, its stopper removed and the attachment 2 placed as shown, and that ether is in the can, air under pressure enters the opening at the end of tube 14 and then liquid ether is forced through the tube 13 and from the apparatus in the form of drops, spray or a stream, according to the 80 attachment employed. The cork disk 12 85 always insures a tight joint because it is forced against the mouth 3 by the force of the frustum and the pressure exerted through the screw 7 and the tighter the application of the screw, the tighter the joint 90 at the disk 12. Because of this tightness of joint at all times and the other features above mentioned, the ether is always under control and does not injure the patient through any defect in the attachment 2. 95

While I have shown and described one embodiment of my invention, it is obvious that it is not restricted thereto, but is broad

enough to cover all structures that come within the scope of the annexed claim.

What I claim is:

In a device of the class described, a cork with openings, one of which has a tube extending to a point near the bottom of an ether can when the device is in place on this can, the other opening being connected to

an air pressure tube, a disk on said cork and attached to said tube, a frustum attached to said disk and means for forcing said frustum against said can to cause the cork to fit with an ether tight joint.

LOUIS SHEINMAN, M. D.
